UNITED STATES PATENT OFFICE.

GEORGE FRANK LORD, OF HOLLY OAK, DELAWARE, ASSIGNOR TO DU PONT FABRIKOID COMPANY, OF WILMINGTON, DELAWARE, A CORPORATION OF DELAWARE.

COMBINED POLISH AND REMOVER OF GREASE AND TAR.

1,356,869.

Specification of Letters Patent. Patented Oct. 26, 1920.

No Drawing.

Application filed March 26, 1917. Serial No. 157,410.

To all whom it may concern:

Be it known that I, GEORGE F. LORD, of Holly Oak, in the county of New Castle, and in the State of Delaware, have invented a 5 certain new and useful Improvement in Combined Polish and Remover of Grease and Tar, and do hereby declare that the following is a full, clear, and exact description thereof.

10 My invention relates particularly to a composition designed to be used for producing a polish upon surfaces of all kinds, particularly enameled, lacquered or varnished surfaces, and to act as a grease and tar remover.

15 The object of my invention is to provide a composition of this character which will effectively polish surfaces of the kind above referred to, and especially surfaces of automobile bodies, and which will, at the same 20 time, effectively act as a grease and tar remover.

25 While my invention is capable of embodiment in many different forms, for the purpose of illustration I shall describe only one form thereof hereinafter. For example, my invention may be carried out by producing a composition of the following character:

30 A composition made in accordance with my invention may be comprised of solvent naphtha 80% and lubricating oil 20%. The lubricating oil may be any oil of the general character used for the lubrication of gasoline motors.

35 Solvent naphtha acts as an effective remover of grease and tar, and, at the same time, operates as a solvent or diluent for the lubricating oil so as to spread a very thin layer of the same over the surface operated 40 upon.

While the portions of the constituents may be varied to some extent, the best results are obtained by a composition of the above proportions. Furthermore, while lubricating oil is the most advantageous oil 45 to use for this purpose, it is to be understood that some other oils may be used instead.

While I have described my invention above in detail, I wish it to be understood

that many changes may be made therein 50 without departing from the spirit of my invention.

I claim:

1. A composition adapted to act both as a polish and as a remover of grease and tar, 55 consisting essentially of a light hydrocarbon solvent and a heavy oil.

2. A composition adapted to act both as a polish and as a remover of grease and tar, 60 consisting essentially of a light hydrocarbon solvent and a heavy hydrocarbon oil.

3. A composition adapted to act both as a polish and as a remover of grease and tar, comprising solvent naphtha and a heavy oil.

4. A composition adapted to act both as 65 a polish and as a remover of grease and tar, comprising solvent naphtha and a heavy hydrocarbon oil.

5. A composition adapted to act both as a polish and as a remover of grease and tar, 70 consisting essentially of a light hydrocarbon solvent and a lubricating oil.

6. A composition adapted to act both as a polish and as a remover of grease and tar, 75 comprising solvent naphtha and a lubricating oil.

7. A composition adapted to act both as a polish and as a remover of grease and tar, comprising a light hydrocarbon solvent and a lubricating oil, in the proportion of substantially 80% solvent and 20% oil.

8. A composition comprising a solvent naphtha and a lubricating oil in the proportion of substantially 80% solvent naphtha and 20% oil.

9. A polish and grease removing composition consisting essentially of an oily constituent adapted to polish a surface and take up grease and dirt therefrom, and a light hydrocarbon solvent adapted to prevent 85 gumming of such constituent.

In testimony that I claim the foregoing I have hereunto set my hand.

GEORGE FRANK LORD.

Witnesses:

MARTIN WM. McHUGH,
KATHERINE E. DOHERTY.
